FOUNTAIN PEN

Application filed February 1, 1926. Serial No. 85,244.

Our invention relates to fountain pens wherein it is desired to provide means for operating the ink sack to collapse the same when it is desired to expel the air or the ink in the sack.

5 A feature of the invention is an extremely simple, inexpensive construction with only two operating parts, namely the lever and the ink engaging or compressing bar. These 10 two parts operate in a manner so as to force the ink sack into a collapsed state when the lever is raised, and to permit the sack to expand when the bar is elevated by lowering the lever.

15 It is also a feature of the invention to provide means for supporting the lever directly by the casing of the fountain pen which may be made of metal or any other suitable material. By a particular construction, yet 20 simple, we lock the lever against disengagement from the casing or barrel of the fountain pen when it is in operating position. It is only possible to remove the lever when the same is rotated into an inoperative position 25 insofar as the bar is concerned and over far enough so as to release it from the casing. This can only be accomplished when the ink sack presser bar is removed or disengaged from the operating lever.

30 Our invention also includes a lever adapted to carry and lift the ink presser bar, including means engageable over the operating end of the lever to lock the lever and bar together against free disengagement, but permitting the same to be separated, if it is desired, thus forming a catch with the inner operating end of the lever and the sack presser bar. This construction provides means for preventing the presser bar from 35 slipping out of the barrel when the ink sack and pen point are removed. Yet the presser bar can be released from the lever by engaging the same and pulling it sufficiently to release the catch.

40 These features, together with other objects and particular form of construction of our fountain pen will be more fully and clearly set forth in the specification and claims.

In the drawing forming part of this specification:

Figure 1 is a sectional view of a fountain pen barrel illustrating our lever and bar sack operating means.

Figure 2 is a similar section illustrating the lever in a position to compress the ink 55 sack.

Figure 3 illustrates the fountain pen barrel with the writing nib, ink sack, and ink sack operating means removed.

Figure 4 illustrates a portion of the fountain pen barrel showing the operating lever in releasing or attaching position as it would appear when it is unlocked from the pivot.

Figure 5 is a perspective view of the lever.

Figure 6 is a perspective view of the ink 65 sack presser bar.

Figure 7 is a section on the line 7—7 of Figure 6.

In the drawing our fountain pen A is adapted to be provided with a writing nib 10, held 70 in the ordinary manner in the section 11, which is provided with the shank 12 and to which is secured the ink sack 13.

The fountain pen A is designed to receive a large ink sack 13 and is constructed with a metallic shell or barrel 14, which is attached to the shank 12 in a manner to hold the barrel 14 rigidly secured to the section 11. The barrel 14 forms a cover for the ink sack 13 and for the lever operating mechanism B, 80 which is adapted to press the sack so that it can be filled with ink.

The lever operating mechanism B includes the finger lever 15 which is formed with an operating end 16, locking fingers 17 which are 85 adapted to engage the barrel 14 to hold the lever in inoperative position or closed against the barrel.

The operating end 18 of the lever 15 is formed with outwardly projecting lugs 19 90 which are adapted to engage in the channels 20 formed in the ink presser bar 21. The engagement of the lugs 19 in the channel 20 causes the presser bar 21 to be lifted or lowered as the lever 15 is operated, as illustrated in Figure 2. Depressions 22 are formed in the flanges which form the channels 20 of the presser bar 21 which form stops so as to limit the movement of the presser bar 20 on the lugs 19. The lugs 19 are adapted to engage 95 100

in the channels 20 freely so that the presser bar 21 can be slid onto the lugs 19 when the lever 15 is pivotally attached to the barrel 14. The construction of the presser bar 21 is such that the spring of the material will permit the lugs 19 to be snapped beneath the depressions 22 at one end so that the presser bar 21 is locked against freely sliding back and forth on the lugs 19, when it is in operation, between the limits of the stops or depressions 22. An opening 23 permits the presser bar 21 to be engaged by a wire or other suitable means so that it can be pulled sufficiently to release it from the lugs 19, permitting the lugs to pass beneath the depressions 22.

The lever 15 is formed with a pivot opening 24 which is adapted to engage the bar 25 formed integral with the barrel 14 and extending across the lever slot 26. The lever 15 is adapted to be locked to the pivot bar 25 so that it will not become disengaged therefrom in operation. To release the lever 15 from the pivot 25 it is necessary to rotate it into the position illustrated in Figure 4, after the presser bar 21 has been disengaged from the lugs 19. The lever 15 cannot be removed from the presser bar until the same is disengaged from the lugs 19. When the lever 15 is rotated into the position illustrated in Figure 4 the slots 28, which extend from the edge of the lever to the pivot opening 24 and which are of approximately the width of the pivot bar 25, permit the lever 15 to be slid over the bar 25 or disengaged therefrom. In attaching the lever 15 it is slid onto the bar 25 through the slots 28 to position the lever as illustrated in Figure 4 and then the lever is rotated so that the operating end 16 will lie with the spring fingers 17 engaging the sides of the slot 26 adjacent the recess 29 which is adapted to receive the flat end 30 of the lever 15.

A feature of primary importance in our invention resides in the simplicity of construction, the small number of parts and the effective operation of the lever and ink sack compressing means. In our fountain pen it is desirable to employ an ink sack with sufficient firmness and of a suitable thickness to the wall of the sack so that a good substantial ink sack is provided having long wearing qualities and being adapted to readily expand in position to draw a large quantity of ink into the same. No spring means is employed for lifting the presser bar 21 from the sack but the particular construction is so designed and arranged as to cause the bar to be lifted away from the ink sack and held up against the inner surface of the barrel 14 when the lever 15 is operated to elevate the bar 21, thereby permitting the ink sack to fully expand and receive a substantial quantity of ink. The spring fingers 17 engage the sides of the slots 26 in the barrel so as to hold the same locked out of operating posi-

tion. In this position the lever holds the presser bar 21 locked in elevated position away from the ink sack 13. The presser bar may be made with or without the indentations 22 and when the bar is held locked up against the inner surface of the barrel by the lever 15 it is held against sliding within the fountain pen. When the lever is released and moved into operating position then the bar 21 may be freely disengaged from the lugs 19. 75

With the metallic barrel of our fountain pen only two operating parts, outside of the barrel, are employed, thereby providing a most simple, yet very effective fountain pen construction. 80

While we have illustrated a particular form and construction of our fountain pen in the drawing we desire to have it understood that the same is only suggestive of a means of carrying out our invention and 85 that the particular construction may be varied and applied to uses other than those above set forth, within the scope of the following claims. 90

We claim:

1. A fountain pen, including a barrel, a pivot bar carried by said barrel, a lever adapted to be supported on said pivot bar and means formed in said lever whereby the same is released from said bar when it is turned beyond 95 operating position.

2. A fountain pen including, an operating lever, a channeled presser bar adapted to be operated by said lever to squeeze the ink sack, lugs formed on said lever for engaging 100 in the channels of said bar and means for pivoting and locking said lever on the pivot until said bar is disengaged from the lugs on said lever.

3. A separable fountain pen ink sack operating means including a presser bar, a lever having a pivot opening formed therein, bar engaging lugs formed on one end of said lever, spring fingers formed on the other end of said lever, said lever having a slot connecting with the pivot opening and positioned in a manner to lock said lever against disengagement until rotated beyond operating position. 105

4. A fountain pen including a barrel, a 115 filler lever and a sack pressing means operable by said lever, said lever having means formed therein adapted to detachably pivot the same to the fountain pen barrel by rotating the lever beyond operating position 120 when said pressing means is out of the fountain pen.

5. A fountain pen lever having means for locking said lever to a pivot and having a slot formed in the lever whereby the lever 125 is only releasable when rotated beyond operating position.

6. A fountain pen ink sack operating means including, a lever, means for detachably supporting said lever, said means hav- 130

ing a pivot opening in said lever, a pivot fixed to the fountain pen, said lever also having a slot communicating with said pivot opening and a presser bar adapted to limit the rotation of said lever on said pivot to hold the lever locked to the pivot, said lever being disengageable from said pivot when said bar is separated from said lever.

7. A presser lever and support including a lever member, a barrel member, a pivot bar formed in said barrel member having recesses formed on either side thereof, said lever having a pivot opening and slots so positioned as to hold said lever locked to said bar until 15 turned out of operating position.

8. A fountain pen, an ink sack presser means including, a lever, a presser bar, said lever being adapted to raise and lower said presser bar, a pivot bar for supporting said 20 lever, said lever having slots formed in the side thereof beyond releasing position when said lever is in operative position, said lever being releasable from said pivot bar by rotating said lever beyond operative position, 25 said presser bar normally holding said operating lever in operative position.

9. A fountain pen including a barrel, a pivot bar on said barrel, a lever having means for releasably locking same in operating position 30 to said pivot bar, and an ink sack presser bar having means to hold said lever against rotating to position to release said lever from said pivot bar.

10. A fountain pen, including a lever, a 35 sack-presser bar operable by said lever, a flat pivot for said lever, said lever having a pivot opening formed therein, and having slot means formed communicating with said pivot opening, said slot means being positioned to be operative to release said lever from said pivot only when said lever is turned beyond normal operating position.
